Primary Examiner — Darlington Ly

(74) Attorney, Agent, or Firm — The Dobrusin Law Firm,
P.C.; Daniel P. Alekynas(57) **CLAIM**The ornamental design for a vehicle bumper, as shown and
described.

DESCRIPTION

FIG. 1 is front and right side perspective view of a vehicle bumper showing my new design;

FIG. 2 is a rear and right side perspective view thereof;

FIG. 3 is a right side elevation view thereof, to which the left
side elevation view is a mirror image;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate portions of the
vehicle bumper that form no part of the claimed design.**1 Claim, 4 Drawing Sheets**| (56)	References Cited
